UNITED STATES PATENT OFFICE.

DAVID F. HAYNES, OF BALTIMORE, MARYLAND.

DESIGN FOR A EWER OR JUG.

SPECIFICATION forming part of Design No. 22,156, dated January 24, 1893.

Application filed December 29, 1892. Serial No. 456,710. Term of patent 3½ years.

To all whom it may concern:

Be it known that I, DAVID F. HAYNES, a citizen of the United States, residing at Baltimore, Maryland, have invented and produced a new and original Design for a Ewer or Jug, of which the following is a specification, reference being had to the accompanying drawings, forming a part hereof.

Referring to the annexed drawings, Figure 1 is an exterior side elevation of the ewer, and Fig. 2 a top view of the same.

I describe the ewer or jug as follows: Its body A between the points *a* and *b* is a frustum of an ellipsoid with the greater diameter at *a*. Between the points *a* and *c* which latter is the base of the collar B which connects the body to the neck C, the body is spheroidal. Depending from the base of the collar B are six decorated points *d*, and near the bottom of the body is a decorated band *f*. The collar B has radial grooves *g*, and the segments or divisions between them are rounded so as

to give a curved termination *h*. The neck C is flared outwardly from the collar B and the curvature at one side is greater than at the other so as to produce the pouring lip E. The top of the lip E is curved as shown at *j*, to about the axis of the body, and from that point a curved depression *k* is formed. The edge *m* of the mouth is flattened as seen from the side, and decorated. The handle F which is decorated with reversed scrolls, connects the rear of the neck immediately below the flattened edge *m* with the body. As seen from the top, the mouth is elliptical owing to the extended lip.

I claim as my invention:—

The design for a ewer or jug as herein shown and described.

DAVID F. HAYNES.
